UNITED STATES PATENT OFFICE.

PETER BROTHERHOOD, OF LAMBETH, ENGLAND.

TRIPLE-CYLINDER ENGINE.

SPECIFICATION forming part of Letters Patent No. 618,775, dated January 31, 1899.

Application filed February 28, 1898. Serial No. 672,034. (No model.)

To all whom it may concern:

Be it known that I, PETER BROTHERHOOD, a citizen of England, residing at Belvedere road, Lambeth, in the county of Surrey, England, have invented certain new and useful 5 Improvements in Triple-Cylinder Engines, of which the following is a specification.

My invention relates to engines worked by fluid under pressure acting in three cylinders 10 which radiate around a central crank-shaft, the fluid acting on the pistons only in the one direction, forcing them successively toward the shaft, while their return strokes are effected by the crank.

15 My present invention consists particularly in detail improvements on the engines described and shown in Letters Patent Nos. 284,372 and 323,270, issued to me respectively September 4, 1883, and July 28, 1885.

20 The improvements will be hereinafter described, and pointed out in the claim, reference being made to the accompanying drawings, in which—

Figures 1 and 2 are two central sections of 25 an engine according to my present invention, taken on planes at right angles to each other. Fig. 3 is a sectional plan of one of the cylinders on the line 3 3 of Fig. 1. Fig. 4 is an elevation of the cam and rubber.

30 Each piston P has through it a slot *p*, which while the piston is making its back stroke partly or wholly coincides with a slot *c* through the rounded outer end C of the connecting-rod, this slot being at such an angle that the 35 slots coincide only while the connecting-rod is moving at an inclination to the right of its central position. Each cylinder has four exhaust cavities or recesses R, which extend longitudinally some distance along the cylinder from the central cavity A, in which the crank B revolves. The crank-shaft D is tubular, giving passage for exhaust. The crank-pin E is also made tubular for the sake of lightness, and to it is fixed a disk F, made 40 with a heavy part *f* to counterbalance the crank-pin, which is also partly counterbalanced by a heavy part *b* of the crank.

On the disk F is a cam G, against which bear three guided rubbers N, one for each 45 valve-stem *s*, which butts against the rubber.

The valve S is of piston form, having a hollow stem inclosing a spring which keeps the stem *s* and rubber N pressed against the cam G. The working fluid is admitted into an annular passage which communicates with the 55 three valve-chests K. Each connecting-rod terminates at its inner end M in a hollow fitting on the crank-pin and has on each side a projecting lip engaged in annular grooves L, formed on the faces of the crank B and the 60 disk F, respectively. The engine operates in the following manner: The piston-valve S being in such a position as to uncover the port at the end of the cylinder, fluid under pressure passes from the valve-chest into the cylinder and propels the piston toward the central shaft until the cam moves the valve S to the position where it covers the port. As the piston approaches the end of its stroke it uncovers the recesses R, allowing a large portion of the fluid which has acted in the cylinder to escape into the central cavity and thence through the tubular shaft D. Soon after the connecting-rod has passed its dead-center, the piston being about to cover the 75 recesses R, the slots *p* and *c* come into coincidence, so that when the recesses R are quite closed against escape the residuary fluid in the cylinder escapes through these slots until the piston completes its stroke, whereupon 80 the action is repeated. As each piston in its turn propels the crank through part of a revolution during its stroke in the one direction and is moved back by the crank continuous revolution of the crank is effected, the connecting-rods being always under stress in 85 only the one direction.

An engine in some respects similar to that which comprises my present improvements was described in my previous specification of 90 English Patent No. 3,989 of 1887. I therefore make no general claim to an engine of this kind; but,

Having thus described the nature of this invention and the best means I know for carrying the same into practical effect, I claim—

The combination of the crank-shaft D having the crank B, of the disk F mounted on the crank and having the weighted part *f*, the cam G arranged upon and supported by the 100

said weighted disk, a series of cylinders, the
pistons, the connecting - rods, the series of
guided rubbers N bearing against the cam
which is mounted on said weighted disk, and
5 the spring - pressed valves S having valve-
stems s acted upon by the rubbers, substan-
tially as described.

In testimony whereof I have hereunto set
my hand in presence of two subscribing wit-
nesses.

PETER BROTHERHOOD.
